UNITED STATES PATENT OFFICE.

ANDREW OLSON, OF CLEVELAND, OHIO, ASSIGNOR TO THE CLEVELAND FOLDING MACHINE COMPANY, OF CLEVELAND, OHIO, A CORPORATION OF OHIO.

FEED TABLE.

Application filed April 3, 1925. Serial No. 20,413.

This invention relates to feed tables for feeding sheets of paper to folding machines, printing presses, etc., and has for one of its objects the provision of means for preventing the sheet from skewing and for insuring that the sheet will be so forwarded as to be presented to the folding machine or printing press in proper alignment.

A further object of the invention is to provide a feed table that is especially adapted for feeding oblong sheets with their shorter sides arranged longitudinally of the table. In the present types of feed tables difficulty is experienced in feeding an oblong sheet, with its shorter sides arranged longitudinally of the table, due to the drag of the side guide which causes one edge of the sheet to lag behind the other. My improvements overcome this difficulty by the provision of side guiding means adapted to move with the sheet and thus eliminate the drag that is produced by the commonly used fixed guide.

Other objects of the invention and the features of novelty will be apparent from the following description taken in connection with the accompanying drawings, of which:

Figure 1 is a plan view of a feed table embodying my invention;

Fig. 2 is a side elevation thereof;

Fig. 3 is a diagrammatic plan showing the arrangement of the belt which acts as the side guide for the sheet;

Fig. 4 is an enlargement of a portion of Fig. 1, showing the take-up mechanism or tension device for the belt, and one of the adjusting devices;

Fig. 5 is a section on the line 5—5 of Fig. 4;

Fig. 6 is a section on the line 6—6 of Fig. 4;

Fig. 7 is an enlargement of a part of Fig. 1, showing the driving means for the belt;

Fig. 8 is a section on the line 8—8 of Fig. 7;

Fig. 9 is a section on the line 9—9 of Fig. 7; and

Fig. 10 is a perspective view of a part of the frame which carries the belt.

Referring to the drawings 20 indicates the frame of the feed table on which the sheets of paper are to be advanced from the feed-in rollers 21 to the take-off rollers 22 and 22', the latter rollers delivering the sheet to the folding machine or printing press or other

mechanism to which it is to be fed. I have illustrated a common form of mechanism for advancing the sheet on the feed table, this mechanism comprising a series of feed rollers 23, suitably journaled on the frame 20, with their axes in the same plane and arranged diagonally with respect to the longitudinal axis of the feed table or direction in which the sheet is advanced. This diagonal arrangement of the feed rollers 23 has the effect of moving the sheet toward the lower side of Fig. 1, as well as longitudinally of the table, the lateral movement of the sheet being for the purpose of properly aligning it and presenting it to the proper position in the folding mechanism or printing press. The rollers 23 are driven by means of an endless belt 24 which frictionally engages with the rollers and is supported by pulleys 25 and 26, the latter being a driving pulley and being mounted on a shaft 27 which is driven in any suitable manner, as by means of the pair of gears 28, from the shaft 29, the latter being supported in bearings 30 and 31 and being driven from the shaft 32 by means of the gears 33. The shaft 32 carries the take-off roller 22 and a driving pulley 34 on which runs a driving belt 35 which extends to any suitable source of power. The take-off roller 22' is mounted on a shaft 36 which is driven from the shaft 32 by the pair of spur gears 37, the shaft 36 being supported at its opposite ends in bearings 38 and 39.

The spaces between the rollers 23 are closed by the plates 40 which are secured, at their opposite ends, to the frame 20 and serve to prevent the sheets from dropping between these rollers.

It has been customary, heretofore, to provide feed tables, of the type illustrated, with stationary side guides against which the edge of the sheet is carried by the feed rollers 23 and this type of side guide has been generally satisfactory for square sheets or oblong sheets that are fed with their longer edges extended longitudinally of the table. However, when it is attempted to feed oblong sheets with their shorter edges longitudinally of the feed table, the drag of the side guide on the edge of the sheet which it engages, tends to make this edge lag behind the opposite edge of the sheet or, in other words, skew the sheet on the feed table so that it will not be properly positioned when

it reaches the take-off rollers 22 and 22'. As before stated, it is an object of this invention to overcome this difficulty and this is accomplished by providing a movable side guide such as the belt 41. In the specific form of the invention illustrated, this movable side guiding mechanism comprises a grooved bar or frame 42 in which one side of the belt 41 is arranged. The bar 42 is supported on a pair of brackets 43 and 44 (see Fig. 1), the brackets being secured to the bar by bolts 45 and having threaded bosses 46 to receive the adjusting screws 47. Each of the screws 47 is rotatably supported in an arm 48 that is fixed on a rod 49, this rod being adjustably supported in the frame 20 and secured by a set screw 50 (see Fig. 6). The screws 47 are held against longitudinal movement in the arm 48 by means of the head 51 and the collar 52, which are arranged on opposite sides of the arm 48. As will be evident from Fig. 6, the bar 42 may be adjusted laterally of the machine by turning the screws 47 and either end of the bar may be adjusted independently of the other, within certain limits.

A bracket 53 is secured on the bar 42 by means of the bolts 54 and carries an idler pulley 59. A bracket 55 is secured on the bearing 39 or other fixed part of the machine by bolts 56 and carries a stub shaft 57 on which there is rotatably mounted a pulley 58 which is formed with a bevel gear 58' at its lower end, this gear meshing with 35 and being driven by a bevel gear 58" on the shaft 36. A bracket 60 is secured to the bar 42, adjacent the bracket 53, and carries an idler pulley 61. At the opposite end of the bar 42 a bracket 62 is secured thereon by means of the bolts 63, this bracket having a slot 64 in its end in which a block 65 slides, this block carrying a stub shaft 66 on which there is rotatably mounted an idler pulley 67. The bracket 62 also carries, on its under side, an idler pulley 68. A lug 69 projects upwardly from the bracket 62 and an adjusting screw 70 is carried by this lug, the screw being provided with a collar 71. There is an upwardly projecting lug 72 on the block 65 and between this lug and the collar 71 there is arranged a compression spring 73 which normally tends to move the block 65 toward the right in Fig. 5, the tension of the spring being adjusted by means of the screw 70.

A bracket 74 is secured on the bar 42, adjacent the bracket 62, and carries the idler pulley 75, this bracket and its idler pulley being substantially like the bracket 60 and pulley 61, as illustrated in Fig. 9.

Referring to Fig. 3, the arrangement of the belt 41 will be clearly seen, that portion of the belt which engages the edge of the sheet and runs in the groove 76, in the bar 42, extending from the pulley 68 to the

pulley 59 and traveling in the direction of the arrow in Fig. 4. The arrangement of the belt in the groove 76 and in contact with the back wall of the groove insures accurate positioning of the belt laterally of the feed table and also provides ample backing for the belt and prevents it from being deflected away from the feed table by the sheet or other cause. From the pulley 59 the belt passes around the driving pulley 58, thence over the pulley 61 to the pulley 75 and around the pulley 67 which acts as a take-up or tension device for maintaining the proper tension in the belt at all times. The velocity of the belt is substantially the same as the velocity of the advancing movement of the sheet along the feed table so that when the edge of the sheet engages the belt, this edge will be carried forward at the same speed as the rest of the sheet and there will be no lagging tendency which would swing the sheet out of alignment. Since the driving pulley 58 is carried on a fixed part of the machine, the bar or frame 42 may be adjusted laterally of the feed table, by means of the screws 47, for the purpose of properly positioning the sheet with reference to the machine with which it is to be fed, without disturbing the drive for the belt 41, the take-up pulley 67 automatically functioning to maintain the proper tension in the belt at all times.

While I have illustrated one particular form of feed table, it is to be understood that the invention is not limited to the use of this particular form and that changes may be made in the details of the construction illustrated without departing from the spirit of the invention as it is defined in the appended claims.

Having thus described my invention, what I claim is:

1. In feed tables, the combination of means for advancing a sheet along said table and to one side thereof, an endless belt arranged along said side so as to engage one edge of the sheet and move therewith, means for driving said belt, and means for adjusting the position of said belt transversely of said table independently of said driving means.

2. In feed tables, the combination of means for advancing a sheet along said table and to one side thereof, an endless belt arranged along said side so as to engage one edge of the sheet and move therewith, means for driving said belt, tension means for keeping said belt taut, and means for adjusting the position of said belt transversely of said table independently of said driving means.

3. In feed tables, the combination of means for advancing a sheet along said table and to one side thereof, a frame arranged parallel with the surface of said table along said side, means for adjusting the ends of said frame transversely of said table, pulleys on said

frame arranged with their axes normal to the surface of the table, a driving pulley in normally fixed relation to said table, an endless belt arranged to run on said pulleys, and tension means for keeping said belt taut in all positions to which said frame is adjustable.

4. In feed tables, the combination of a plurality of driven rollers arranged with their axes at an angle to the direction in which the sheet is advanced along said table, a frame forming a side for said table and toward which the sheet is moved by said rollers, means for independently adjusting the ends of said frame transversely of the table, pulleys on said frame arranged with their axes normal to the surface of the table, a driving pulley in normally fixed relation to said table, an endless belt arranged to run on said pulleys with the portion engaging the first-mentioned pulleys running in the direction in which the sheet is advanced and adapted to be engaged by one edge of the sheet, and tension means for keeping said belt taut.

5. In feed tables, the combination of means for advancing a sheet along said table and

to one side thereof, an endless belt arranged along said side so as to engage one edge of the sheet and move therewith, means for driving said belt, means for adjusting the position of said belt relative to said table, and a positioning member adjustable with said belt engaging the side of said belt that is away from said table and preventing deflection away from the table of that portion of the belt that is engaged by the sheet.

6. In feed tables, the combination of means for advancing a sheet along said table and to one side thereof, an endless belt arranged along said side so as to engage one edge of the sheet and move therewith, means for driving said belt, means for adjusting the position of said belt relative to said table, and a positioning member adjustable with said belt having a groove in which that portion of the belt that is engaged by the sheet runs, the wall of said groove serving to back up the belt and prevent deflection thereof away from said table.

In testimony whereof, I hereunto affix my signature.

ANDREW OLSON.
